Plaskolite, Inc., Columbus, Ohio

Filed Apr. 29, 1974, Ser. No. 465,061

Term of patent 14 years

Int. Cl. D25—01

U.S. Cl. D13—6

FIG. 1 is a perspective view of a foldable panel-holding strip or similar article showing my new design in the folded position, said strip being shown broken away to indicate indeterminate length;

FIG. 2 is an enlarged sectional view taken on line 2—2 of FIG. 1;

FIG. 3 is a perspective view in the open position, the strip being shown broken away to indicate indeterminate length;

FIG. 4 is an enlarged sectional view taken on line 4—4 of FIG. 3.

The underside of the strip is substantially a mirror image of the side shown in FIG. 1.

I claim:

The ornamental design for a foldable panel-holding strip or similar article, substantially as shown and described.
